(57) **CLAIM**

We claim an ornamental design for an audio control device, as shown and described.

DESCRIPTION

A portion of the disclosure of this patent document may contain material which is subject to copyright protection. This patent document may show and/or describe matter which is or may become a trademark or trade dress of the owner. The copyright and trademark/trade dress owner has no objection to the facsimile reproduction by any one of the patent document or the patent disclosure as it appears in the Patent and Trademark Office patent files or records, but otherwise reserves all copyrights, trademarks and trade dress rights whatsoever.

FIG. 1 is a perspective view of an audio control device showing the claimed design;

FIG. 2 is another perspective view of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1;

FIG. 8 is a bottom plan view of FIG. 1; and,

FIG. 9 is an enlarged view of the portion indicated by the dot-dash circle 9 of FIG. 1.

The dot-dash lines represent the boundary of an enlarged area which forms no part of the claimed design.

The broken lines in the drawings represent unclaimed subject matter and form no part of the claimed design.
